(57) CLAIM

The ornamental design for a wall-mountable rack for wine bottles, substantially as shown and described.

DESCRIPTION

FIG. 1 is a front, top, and right side perspective view of a first version of the invention.

FIG. 2 is a right side view thereof. Due to symmetry it is also representative of a left side view, a top view, and a bottom view; and,

FIG. 3 is a front view thereof.

The broken line showing is for environmental purposes only and forms no part of the claimed design.
